UNITED STATES PATENT OFFICE.

HARRY H. DELACROIX, OF PHILADELPHIA, PENNSYLVANIA, ASSIGNOR TO
MACKELLAR, SMITHS & JORDAN, OF SAME PLACE.

DESIGN FOR A FONT OF PRINTING-TYPES.

Specification forming part of Design No. 8,894, dated January 11, 1876; application filed November 24, 1875.
[Term of Patent 7 years.]

To all whom it may concern:

Be it known that I, HARRY H. DELACROIX, (assignor to MACKELLAR, SMITHS & JORDAN,) of the city and county of Philadelphia, Pennsylvania, have invented and produced a new and original Design for a Fout of Printing-Types, of which the following is a specification:

The nature of my design is clearly shown in the accompanying typographic impressions, to which reference is had; and consists of a

letter of the class known as Celtic, made heavier than such letters usually are, and having angular corners, as shown.

What I claim as new is—

The design for a font of printing-types, as shown.

HARRY H. DELACROIX.
